UNITED STATES PATENT OFFICE.

WILLIAM O. STARK, OF CHICAGO, ILLINOIS, ASSIGNEE TO BULLOCK TRACTOR COMPANY,
A CORPORATION OF ILLINOIS.

CATERPILLAR-TRACTOR.

1,124,351.

Specification of Letters Patent. Patented Jan. 12, 1915.

Application filed August 20, 1913. Serial No. 785,673.

To all whom it may concern:

Be it known that I, WILLIAM O. STARK, a resident of Chicago, in the county of Cook and State of Illinois, a citizen of the United States of America, have invented certain new and useful Improvements in the Caterpillar Type of Tractors; and I do hereby declare that the following description of my said invention, taken in connection with the accompanying sheets of drawings, forms a full, clear, and exact specification, which will enable others skilled in the art to which my said invention appertains to make and use the same.

15. The object of this present invention is the production of an efficient, serviceable and durable tractor of the caterpillar type, one that can be easily handled; that can be operated upon all kinds of roads and in the field, and that can be readily turned within the smallest possible radius.

Other objects of this invention will hereinafter more fully appear.

This invention has general reference to 25 the caterpillar type of tractors, and it consists, essentially, in the novel and peculiar combination of parts and details of construction, as hereinafter first fully set forth and described and then pointed out in the 30 claims.

In the drawings already mentioned, which serve to illustrate this invention more fully and form a part of this specification, Figure 1 is a side-elevation of this improved tractor, 35 minor and non-essential details being omitted. Fig. 2 is a transverse sectional elevation on line 1—1 of Fig. 1. Fig. 3 is a transverse sectional elevation on line 2—2 of said Fig. 1. Fig. 4 is a plan of the frame 40 structure of this machine.

Like parts are designated by the same characters and symbols of reference in all the figures.

Referring to Fig. 4, the frame structure 45 of this machine comprises two side-members 12, 13, preferably constructed of commercial I-beams, the rear ends of which are inwardly deflected to connect to two longitudinal frame-members 14, 15, located parallel to 50 said I-beams 12, 13, and extending rearwardly beyond the same. These two frame-members 14, 15, are at their rear ends connected by two, preferably channel bars 16, 17, and at a suitable distance from the rear 55 end by a cross-channel bar 18, while near the forward end there is an I-beam 19, and at

the forward end a transverse I-beam 20, there being located between the forward I-beam 20 and the channel bar 18, a further I-beam 18^a, reaching transversely from the outer I-beam 12 to the opposite I-beam 13. Upon the rearwardly located channel bars 16, 17, and 18 there are placed and secured two channel bars 21, 22, in parallel spaced relation upon which channels there is located a bed-plate 71, upon which is mounted an internal combustion motor A of any suitable construction, by which the machine is operated as will hereinafter more fully appear.

In about the middle of the transverse channels 16, 17, and above and below the same there are secured perforated plates 23—24 constructed to receive the pintle or king-bolt 25, of a fifth-wheel, as it were, 26, 75 from which there are depending three brackets 27, 28 and 29; the lower ends of which form bearings for an axle 30, upon which are mounted two trailing wheels 31, 32, there being rearwardly projecting from 80 the channel 16 a draw-iron 33 or other suitable contrivance by which the tractor may be coupled to any vehicle that may be connected thereto. These two trailing wheels operate caster-wheel fashion, the traction 85 mechanism being at the forward end of the machine, as will be subsequently described.

At the forward end of the machine there is transversely located a rectangular frame comprising two side beams 34, 35, and two 90 pairs of end beams 36, 37. This rectangular frame which I shall hereinafter term the truck-frame, is supported above the four longitudinal beams 13, 15, 14, 12, by four short I-beams 38, 39, 40, and 41; and it is 95 constructed to receive the trucks proper, in the following manner. Depending from the end-beams of the truck frame are plates 42, 43, secured underneath the transverse beams by angle-bars 44, 45, said plates being stiffened to prevent lateral movement by pairs of braces 46, 47. The lower ends of these plates carry bearings 48, 49; and pending from the longitudinal beams 12, 13, there are further bearings 50, 51, said bearings being 100 in alignment to receive pivots 52, 53, of two pairs of rocking arms 54, 54^a, 55, and 55^a, there being two shafts 56, 57, mounted in the tubular pivots 52 and 53, upon which shafts are secured sprocket-wheels 58, 59, 110 which sprocket-wheels are the drives for two caterpillar chains 60, 61, which chains may

be of any desired construction although I prefer a specially constructed chain which performs the subject matter of a copending application for patent filed by me. These 5 chains and their mountings are alike, so that a description of one of these devices will also apply to the other thereof.

At the ends of the rocking arms 55, 55^a, Figs. 1 and 2, there are mounted shafts 62, 10 63, upon which there are secured sprocket wheels 64, 65, over which the chain 61 is trained. These two end sprockets are smaller in diameter than the driving sprocket 59 so that the chain bears on the 15 ground only directly underneath the driving sprocket 59. By this construction the two points of the chains where they bear upon the ground over which the machine is moving, form, as it were, pivotal points so that 20 if one caterpillar were to remain stationary and the other were moving, the stationary one would be the pivotal point on which the machine would turn. This construction is of great importance since it enables the machine 25 to be turned in the smallest possible space. The rocking arms 54, 54^a and 55, and 55^a permit the caterpillars to rise and lower at either end, and to follow the undulations of the ground over which the machine is being 30 moved, with the greatest of ease.

The driving sprockets are rotated by mechanism actuated by the motor A in a peculiar manner which said operating mechanism forms the subject matter of an application 35 filed concurrent with the present one, and needs not be here described in detail except to state that each caterpillar operates entirely independent of the other, whereby the steering and the propelling of the machine 40 is accomplished by varying the speed of the traction means, an increase of speed of the right caterpillar causing the machine to turn to the left, while an increase of speed of the left caterpillar produces the opposite result 45 or, which will be the same, a decrease in speed of one or the other of the caterpillars causes the machine to deviate from its course in the corresponding direction. This driving mechanism, briefly described, includes a 50 main motor shaft 66, longitudinally disposed on the main frame, a pair of driving friction disks 67, 67^a, fastened to said main shaft, a further pair of driven friction disks 68, 68^a, mounted in suitable bearings 55 at right angles to, and between the driving disks and constructed to engage either of said two driving disks, and gearing 69, 70, connecting the shafts of the driven friction disks to the driving sprocket wheels.

60 In motors of the internal combustion type, as shown, liquid fuel is required which, if desired, may be contained in a tank B, Fig. 2, superposed by a water reservoir C mounted on one side of the truck-frame, and a 65 radiator D placed at the opposite side of

said truck-frame, these tanks and containers being indicated by dotted lines in Figs. 1 and 2.

I have heretofore described with considerable minuteness the construction of this machine, but I desire it understood that many of these details may be changed and parts omitted without departing from the scope of this invention.

Having thus fully described this invention, I claim as new and desire to secure by Letters Patent of the United States:

1. A traction engine including a longitudinally disposed main frame, a motor mounted upon said main frame at its rear end, a pair of swiveling trailing wheels constructed to support the said main frame at its rear end, a transverse frame mounted above said main frame at the forward end thereof, a pair of downwardly extending plates in spaced relation, located at each end of said transverse frame, a bearing at the lower end of each plate, a shaft in each pair of adjacent plates, a sprocket driving wheel mounted on each shaft between said adjacent plates, a pair of horizontally disposed rocking arms between each pair of adjacent plates, there being tubular trunnions medially of said arms constructed to engage the bearings of said plates, said shafts extending inwardly through and beyond the inner tubular trunnions, bearings at the ends of said rocking arms, shafts in said bearings, driven sprockets mounted on each of the latter shafts, an endless traction belt 100 trained over each pair of end-sprockets and the medial driving sprocket, and an independently operating pair of driving mechanisms connected to said motor and each of said endless traction belts, said driving 105 mechanisms being constructed to move said traction belts in forward and backward directions.

2. In a traction engine, the combination, of a longitudinally disposed main frame, 110 including side-beams in parallel spaced relation and end and medial beams connecting said side beams, a pair of trailing wheels at one end of said main frame and supporting the rear end of said machine, a motor mounted upon the main frame at the rear end thereof, a bed-plate mounted upon said main frame medially of its length, a transverse frame at the front end of said main frame mounted upon said main frame a distance above the upper flanges of said main frame, pairs of side-plates pending from the ends of said transverse frame, bearings in alignment at the ends of each pair of pendant plates, a pair of rocking arms medially pivoted in said bearings, shafts in said rocking arms, there being tubular trunnions in the center of said arms engaging said bearings, said shafts extending inwardly through and beyond the inner trun- 125 130

- nions, driving sprocket wheels mounted on each shaft between adjacent pairs of pendant plates, bearings at the terminals of said rocking arms, shafts in the latter bearings,
5 driven sprocket wheels upon each shaft located between adjacent ends of said rocking arms, an endless traction belt trained over said driven and driving sprockets, said driving sprockets being larger in diameter than
10 the driven sprockets, driving mechanism located upon said bed-plate, and gearing connecting said motor to the protruding
shaft-ends of said driving sprockets, said driving mechanism being constructed to move said endless traction belt in both a 15 forward and backward direction.
- In testimony that I claim the foregoing as my invention, I have hereunto set my hand in the presence of two subscribing witnesses.

WILLIAM O. STARK.
